UNITED STATES PATENT OFFICE.

ALFRED VON HEYNE, OF BERLIN, GERMANY.

LOCKING DEVICE FOR BOXES AND THE LIKE.

No. 926,742.

Specification of Letters Patent.

Patented July 6, 1909.

Application filed January 8, 1909. Serial No. 471,319.

To all whom it may concern:

Be it known that I, ALFRED VON HEYNE, subject of the German Emperor, residing at No. 19 Jägerstrasse, Berlin, Germany, have invented new and useful Improvements in Locking Devices for Boxes and the Like, of which the following is a specification.

This invention relates to a locking device for boxes and the like, wherein undercut and preferably dovetailed lugs are adapted to be slid and secured on the lid in corresponding recesses or grooves of the sides.

The invention is essentially characterized by the fact that the lugs enable the box to be opened on two sides at least and in case of need to completely extend over the underside of the lid so as to serve as reinforcing battens thereof against damage during transport and shipment.

Three constructional forms of a box lid locking device according to the invention are shown in the accompanying drawings by way of example.

Figure 1 is a plan of the first constructional form of the box with partly inserted lid and adjacent locking screw. Fig. 2 is a bottom view of the lid of Fig. 1. Fig. 3 is a vertical section according to line $x-x$ of Fig. 1, but showing in contradistinction to the latter the complete locking position and inserted locking screw. Fig. 4 is a plan of the second constructional form of the box with lid partly inserted and partly broken away and with adjacent locking screw. Fig. 5 is a bottom view of the lid of Fig. 4. Fig. 6 is a vertical section according to line $y-y$ of Fig. 4 but showing in contradistinction to the latter the complete locking position and inserted locking screw. Fig. 7 is a plan of the third constructional form of the box with partly inserted lid and adjacent locking screw. Fig. 8 is a bottom view of the lid of Fig. 7. Fig. 9 is a vertical section according to line $z-z$ of Fig. 7, but showing in contradistinction to the latter the complete locking position and inserted locking screw.

In the first constructional form according to Figs. 1-3, there is provided on the inner side of the lid a a middle transverse batten b which is dovetailed in its two longitudinal sides and adapted to be slid in the box d provided with corresponding grooves c . In the locking position (Fig. 3), the box may be locked by a screw e with fitting f and sealed by a seal or sealing stamp and the like placed

over the former. As the transverse batten b has the same cross-section in its entire length, the sliding path of the lid a is equivalent to the whole length of the transverse batten b . 60

In the second constructional form according to Figs. 4-6, there are provided on the inner side of the lid g two intermediate transverse battens h , which are dovetailed on the enlarged ends i of their longitudinal sides and adapted to be slid in the box l provided with corresponding grooves k . In the locking position (Fig. 6) the box may be locked by a screw m with fitting n and sealed by a seal or sealing stamp and the like placed over the 70 former.

According to the constructional form of Figs. 4-6 in contradistinction to that of Figs. 1-3, the lid g according to Fig. 4 may be so placed that the end-enlargements i of the 75 transverse battens h are located in front of their corresponding box grooves k and the sliding path of the lid g according to the arrow 1 need only be equivalent to the length of the end-enlargements i . 80

In the third constructional form according to Figs. 7-9, there are provided on the inner side of the lid o two external transverse battens p , which are dovetailed on their inner longitudinal sides and adapted to be slid in 85 the box r provided with correspondingly recessed corners q . In the locking position (Fig. 9), the box may be locked by a screw s with fitting t and sealed by a seal or sealing stamp placed over the former. 90

According to the constructional form of Figs. 7-9 in contradistinction to that of Figs. 1-3 and that of Figs. 4-6, the lid o may not only be slid in a straight line but also placed according to Fig. 7 in such a manner that in 95 this case, only one corner-groove q engages with its outer batten p and the complete sliding path of the lid o according to the arrows 2, 3 is then in the form of a circle.

Having now particularly described and 100 ascertained the nature of my said invention and in what manner the same is to be performed, I declare that what I claim and wish to secure by Letters Patent is:—

1. A box having an open top and provided 105 with a locking portion in one of its walls, the length of said portion equal to but not exceeding the thickness of said walls, and a lid for said box having a locking portion formed to fit the locking portion in said wall, substantially as and for the purpose set forth. 110

2. A box provided with undercut locking

portions disposed in the margins of its walls between the ends thereof, said portions having a length not exceeding the thickness of one of said walls, and a lid having similarly formed locking portions between its ends and of a length less than the width or length of said lid.

3. A box provided with undercut locking portions disposed in the margins of its walls and having a length not exceeding the thickness of one of its walls, and a lid having similarly formed locking portions of a length less than the width or length of said lid.

4. A box provided with undercut locking portions disposed in the margins of its walls and having a length not exceeding the thickness of one of its walls, and a lid for said box having cleats extending across one dimension thereof, said cleats having similarly formed

portions adapted for engagement and disengagement with said box portions.

5. A box provided with undercut box portions disposed in the margins of its walls and having a length not exceeding the thickness of one of its walls, and a lid having cleats extending across one of its dimensions, portions of said cleats having locking portions formed similarly to said box locking portions and of a length less than the width or the length of said lid.

In witness whereof I have hereunto signed my name this 16th day of December 1908, in the presence of two subscribing witnesses.

ALFRED VON HEYNE.
